(57) **CLAIM**

The ornamental design for a fabric chair restraint for baby, as shown and described.

DESCRIPTION

FIG. 1 is a perspective view of a fabric chair restraint for baby, showing my new design in condition of use;

FIG. 2 is a front elevation view of the invention;

FIG. 3 is a rear elevation view of the invention;

FIG. 4 is a left-side elevation view of the invention, with the top strap shown in a different position from FIGS. 2 and 3;

FIG. 5 is a right-side elevation view of the invention, with the top strap shown in the position of FIG. 4;

FIG. 6 is a top plan view of the invention, with the top strap shown in the position of FIG. 4; and,

FIG. 7 is a bottom plan view of the invention, with the top strap shown in the position of FIG. 4.

The broken lines showing a baby in FIG. 1 are included for the purpose of illustrating the invention in use, and form no part of the claimed design.
